UNITED STATES PATENT OFFICE.

WILLIAM F. SMITH, OF BROOKLYN, NEW YORK, ASSIGNOR TO WESTERN ELECTRIC COMPANY, INCORPORATED, OF NEW YORK, N. Y., A CORPORATION OF NEW YORK.

TWISTING-MACHINE.

1,356,834.

Specification of Letters Patent. Patented Oct. 26, 1920.

Original application filed January 17, 1916, Serial No. 72,493. Divided and this application filed February 12, 1917. Serial No. 148,273.

To all whom it may concern:

Be it known that I, WILLIAM F. SMITH, a citizen of the United States, residing at Brooklyn, in the county of Kings and State 5 of New York, have invented certain new and useful Improvements in Twisting-Machines, of which the following is a full, clear, concise, and exact description.

This invention relates to twisting machines, and is a division of Patent No. 10 1,263,478, issued April 23, 1918.

This invention relates particularly to machines for forming a plurality of tinsel threads into a stranded conductor for use in 15 telephone or switchboard cords.

One object of this invention is to produce a machine for stranding a plurality of tinsel threads into a symmetrical flexible conductor in such a manner that any strain or 20 stress applied to the conductor is uniformly and equally distributed over the several threads, thereby greatly increasing the conductor life.

A further object of this invention is to 25 provide means for applying tension to the tinsel threads so that the tension will be uniform for all threads regardless of the direction of rotation of the twisting head. Preferably, this is accomplished by providing 30 a flexible belt in engagement with the spool supports and equalizing links in connection therewith for distributing the tension thereon.

This invention will be fully understood 35 from the following description, considered in connection with the accompanying drawings, in which—

Figure 1 is a side elevation of a twisting machine embodying this invention; 40 Fig. 2 is a plan view of the twisting head with parts broken away to show the tension-equalizing and adjusting means;

Fig. 3 is a sectional view of the twisting head showing further the tension-equalizing 45 and adjusting means; and

Fig. 4 is a sectional view of a portion of the twisting head.

Referring to Fig. 1 of the drawings, 10, 11 and 12 are vertical frame members of the 50 twisting machine.

Members 11 and 12 are connected near the top of the machine by a horizontal member

13, and members 10 and 11 are connected near the base of the machine by 14, which is a horizontal extension of member 10.

The twisting head 15 shown in Fig. 2 is mounted on the supporting member 14 and rotates in ball-bearings of any well-known construction. On the twisting head 15 and close to the periphery thereof is mounted a 55 number of spool supports or spindles 20 for carrying spools or bobbins 21. The spindles 20 are journaled in ball-bearings 22 and 23 of any well-known construction. On the sides of the spindles are spring members 24, 60 which press against the inner peripheries of spools 21 for holding them in place and against rotation relative to the spindle upon which they are mounted.

At the center of the twisting head is an 70 auxiliary frame 25 with outwardly extending arms 26, near the ends of which are secured, by means of screws 27, wheels 28 having two grooves in each of the peripheries thereof. Just below and in alignment 75 with each wheel 28 is a grooved wheel 29 secured to a vertical plunger 30 by means of screw 31. The vertical plunger 30 passes through an opening in the frame 15 and auxiliary frame 25, and is normally so held that 80 the lower end of the plunger is flush with the frame 15 at the opening therethrough. To each of the spindles 20 between ball-bearings 22 and 23 is secured a sleeve 32 having an annular groove 33 therein. A circular 85 belt 34 passes around the spindles and in grooves 33 for applying the necessary tension to the tinsel threads. To each end of the belt 34 is rigidly secured a metal tip or socket 35, which is pivotally secured, by 90 means of screw 36, to equalizing links 37 pivotally supported on block 38, which is adapted to slide on threaded rod 39.

It will be seen that with the ends of the belt held in a definite fixed position, the rotation of the spindles would cause the flexible belt to impart very non-uniform tension, that is, the rotation of the several spindles would cause the belt to impart the greatest tension to the spindles immediately 95 on one side of the fixed position of the belt, and the least tension to the spindles immediately on the opposite side of the fixed position, depending upon the direction of ro-

- tation of the spindles. By means of equalizing links 37, the slack in the belt on one side of the links is given over to the opposite side, thereby maintaining a uniform tension 5 on all of the spools. By turning the rod 39, the threaded portion thereon engages block 40 and imparts a longitudinal movement thereto which forces compression spring 41 against block 38, which in turn, through the 10 equalizing links 37, draws the belt 34 tighter around the spindles. It will, therefore, be seen that by the turning of a single member 39, the tension on the belt may be easily and readily adjusted.
- 15 The twisting head may be driven in any well-known manner, preferably by applying power to the sprocket wheel 43, as disclosed more fully in my copending application, Serial No. 72493.
- 20 On the front of the machine is a bracket 78 for supporting a spool 79 carrying a tinsel thread or filler 80 for forming the center of the stranded conductor. Spring 81 and brake member 82 are carried by the 25 bracket 78 for applying tension to the filler 80 as it is drawn from the spool 79.

The operation of the machine is as follows:

- 30 The tinsel thread or filler 80 is drawn from spool 79 around grooved pulley 83, up through the center of the twisting head 15 and the auxiliary frame 25, and thence to the periphery of grooved wheel 85, at which point several threads of tinsel 86 are applied around the filler. The tinsel threads 35 86 are drawn from spools 21 over and along one groove of wheels 28, thence down and around grooved wheels 29, thence up and along the other groove of wheels 28, thence 40 up to the periphery of the grooved wheel 85, where they are formed around the filler 80. From this point the stranded conductor passes over and around grooved wheel 87, thence back along another groove 45 in wheel 85, and thence on to a suitable take-up device. Grooved wheels 85 and 87 are mounted on the cross-member 13 and are preferable to a bushing for forming tinsel threads into a stranded conductor, there being 50 less cutting effect between the tinsel and rotatable wheels than between the tinsel and a bushing. The tinsel threads 86, in passing around grooved wheels 29, normally counteract the weight of the plunger 30,

the weight of wheels 29 and the action of 55 compression springs 88, so that the ends of the plunger 30 are held flush with the openings in the twisting head 15, through which they pass.

Should any one of the tinsel threads carried by the twisting head break or slacken, the plunger 30, supported thereby, falls to the position shown in Fig. 4, and the end of the plunger, extending below its respective opening in the twisting head, may engage 65 a tripping device for automatically stopping the rotation of the twisting head, as fully disclosed in my copending application, Serial No. 72493.

What is claimed is:

1. In a machine for twisting strands, a twisting head, a plurality of spool supports carried thereby, tensioning means comprising a flexible member in engagement with all of said spool supports, and means for 75 automatically maintaining uniform tension on all of the spool supports.
2. In a machine for twisting strands, a twisting head, a plurality of spool supports carried thereby, tensioning means common 80 to all of said spool supports, and adjustable members for equalizing and varying the tension of said tensioning means on said spool supports.
3. In a machine for twisting strands, a 85 revoluble head, a plurality of spool supports carried thereby, tensioning means common to all of said spool supports comprising a flexible belt, and equalizing means therefor comprising equalizing links.
4. In a machine for twisting strands, a 90 revoluble head, a plurality of spool supports carried thereby, a brake-band engaging said spool supports, equalizing links for said brake-band, and a single adjusting means 95 for controlling the tension of the brake-band.
5. In a machine for twisting strands, a revoluble head, a plurality of spool supports carried thereby, tensioning means for all 100 said spool supports, equalizing links connected to said tensioning means, and a single member for adjusting said tensioning means through the instrumentality of said equalizing links.

In witness whereof I hereunto subscribe my name this 6th day of Feb., A. D. 1917.

WILLIAM F. SMITH.
